UNITED STATES PATENT OFFICE.

JOSEPH A. HURLEY, OF NEW YORK, N. Y.

BOOKBINDER'S TRUCK AND TABLE.

1,170,268.

Specification of Letters Patent.

Patented Feb. 1, 1916.

Application filed August 31, 1915. Serial No. 48,277.

To all whom it may concern:

Be it known that I, JOSEPH A. HURLEY, a citizen of the United States, residing at New York city, in the county of New York and State of New York, have invented new and useful Improvements in Bookbinders' Trucks and Tables, of which the following is a specification.

This invention relates to a combined truck and table designed especially to be used by bookbinders and it consists in the novel features hereinafter described and claimed.

An object of the invention is to eliminate the present procedure of carrying the loose leaves in a bindery from the place where the leaves are cut, to the stitcher or the transporting of stacks of these leaves on a truck and then transferring them to the stitcher's table.

Another object of the invention is to provide in a table of the character indicated means for supporting the stack of leaves in an inclined position with relation to a horizontal whereby the leaves will be retained in proper position upon the table as the table is moved and the edges of the leaves will be sufficiently separated to enable the binder to readily grasp a signature of leaves to remove the same from the stack and table.

With these objects in view the table comprises a frame mounted upon casters and having a bottom panel mounted thereon, the upper surface of which is in an inclined position with relation to a horizontal. A shelf is adjustably mounted with relation to the said panel and may be projected beyond the forward edge thereof to be used as a means for abutting or squaring the ends of the leaves up preparatory to stapling or fastening them together in the usual manner.

A back and side frame is mounted upon the first mentioned frame and carries back and side panels. The back panel is provided with a surface which is disposed at an angle approximately equal to a right angle with relation to the upper surface of the bottom panel, but the said surface of the back panel is inclined at an angle with relation to a perpendicular erected from a horizontal line.

In the accompanying drawing:—Figure 1 is a perspective view of the combined truck and table. Fig. 2 is a transverse sectional view of the same. Fig. 3 is a detail sectional view of parts of the frame of the table.

The table comprises a bottom frame which includes the vertical standards 1 formed of

pipe sections or other suitable tubular members. These standards are connected together at their upper ends by cross bars 2 which join at their ends with couplings 3 mounted at the upper ends of the standards 1. Suitable braces 4 are interposed between the intermediate portions of the standards 1 and the cross bars 2. The standards 1 carry at their lower ends journaled caster wheels 5.

A bottom panel 6 is mounted upon the cross bars 2 and the said panel is provided with an upper surface which is inclined with relation to a horizontal. The panel 6 is provided at its forward edge with a slot 7 in which is slidably mounted a shelf 8. The said shelf 8 carries at its inner portion a set screw 9 which may be tightened against the under side of the panel 6 whereby the said shelf may be held at an adjusted position with relation to the said panel. The shelf 8 is provided at its underside and in the vicinity of its outer edge with a knob 2 which may be used as a handle grip for moving the said shelf.

A frame is superimposed upon the frame of which the standards 1 and cross bars 2 are components and the said superimposed frame comprises rods 11 which fit at their lower ends in the upper portions of some of the standards 1 and serve as means for bracing or strengthening the standards 1. The rods 11 are held in position in the standards 1 by means of bolts 12 which pass transversely through the rods and standards and also serve as means for securing one end of the braces 4. Cross rods 13 connect the upper ends of the rods 11 together and a back panel 14 is secured at one edge to one of the cross rods 13 and at its other edge to one of the cross bars 2 as is shown in Fig. 2 of the drawing. The panel 14 is provided with a forward surface which is at a right angle to the upper surface of the panel 6 and the forward surface of the panel 14 is inclined at an acute angle with relation to a perpendicular erected from a horizontal. A side panel 15 is mounted upon the rods 11 and 13 at one end of the table and the lower edge of the said panel 15 is connected with one of the cross bars 2 as best indicated in Fig. 1.

In use a stack of leaves is placed upon the upper surface of the bottom panel 6 and the edges of the said leaves bear against the forward surface of the back panel 4. In view of the fact that the forward surface of

- the panel 14 and the upper surface of the panel 6 are approximately at a right angle with relation to each other, the stack of leaves will be held with their edges in alignment but the said stack is inclined slightly at an angle with relation to a perpendicular erected from a horizontal. Therefore, as the table is moved over the floor by trundling the same upon the caster wheels 5, the stack 5 of leaves will remain in position upon the table, and when it is desired to remove the leaves for stapling or otherwise securing them together, the signature of leaves removed from the stack may be abutted up at 10 their edges upon the upper surface of the shelf 8 whereby the edges of the leaves removed are brought in proper position with relation to each other preparatory to stapling or securing them together.
- 15 20 From the above description taken in conjunction with the accompanying drawing, it will be seen that a combined truck and table especially adapted to be used by book binders is provided and that the said table 25 is a simple and durable structure and may be conveniently used for transporting the leaves from place to place without danger or the leaves falling from the table or becoming disarranged with relation to each other.
- 30 Having described the invention what is claimed is:—
1. A table comprising a wheel mounted

frame, a bottom panel mounted thereon and having an upper surface disposed at an angle with relation to a horizontal, a shelf 35 adjustably mounted upon the bottom panel, means for securing the shelf at an adjusted position with relation to the bottom panel, a back panel mounted upon the frame having a forward surface inclined at an angle 40 with relation to a perpendicular erected from a horizontal, the forward surface of the back panel being approximately at a right angle to the upper surface of the bottom panel.

2. A table comprising a wheel mounted frame including vertically disposed hollow standards, a superimposed frame including rods which fit in these said standards, means for securing the rods in the standards, a 50 bottom panel mounted upon the frame and having an upper surface inclined at an angle with relation to a horizontal, a back panel mounted upon the said rods and the said frame and having the forward surface inclined at an angle with relation to a perpendicular erected from a horizontal.

In testimony whereof I affix my signature in presence of two witnesses.

JOSEPH A. HURLEY.
